UNITED STATES PATENT OFFICE.

GILBERT P. RITTER, OF WASHINGTON, DISTRICT OF COLUMBIA.

DRAFT APPLIANCE FOR RAILWAY-VEHICLES.

1,256,259.

Specification of Letters Patent. Patented Feb. 12, 1918.

Application filed January 25, 1916. Serial No. 74,149.

To all whom it may concern:

Be it known that I, GILBERT P. RITTER, a citizen of the United States, residing at Washington, in the District of Columbia, have invented certain new and useful Improvements in Draft Appliances for Railway-Vehicles; and I do hereby declare the following to be a full, clear, and exact description of the invention, such as will enable others skilled in the art to which it appertains to make and use the same.

My invention relates to draft appliances for railway vehicles and its primary object is to produce a friction draft gear in which the elements thereof are so constructed and arranged that a mechanism having a very high capacity to resist draft and buffing shocks may be made of sufficiently compact form to enable it to be readily located in the comparatively narrow space between steel car center-sills having the present standard spacing. A further object of the invention is to produce a friction draft gear which may be easily applied to or removed from the railway vehicle. A still further object of the invention is to form the rigid parts of the mechanism so as to conduce to lightness of structure, strength and simplicity of manufacture. Other features of invention, residing in particular combinations of elements and special forms of parts will hereinafter appear and be pointed out in the claims.

Generally stated, these several objects may be accomplished by employing in a friction draft gear a centrally arranged friction element having its upper and under sides in slidable contact with friction elements which press against the friction faces of said central friction element, by vertically dispensing, one above another, the springs or spring units which are employed to induce the pressure between the friction elements, and by extending the central friction member between the spring units.

In the drawings illustrating the best mode in which I have contemplated applying the principle of my invention,

Figure 1 is a view, partly in side elevation and partly in vertical section, of a draft gear embodying the invention, a portion of the car framing being also shown.

Fig. 2 is a view, partly in plan and partly in horizontal section, of a structure illustrated in Fig. 1.

Fig. 3 is a vertical central section of the

mechanism, showing also a portion of the car framing.

Fig. 4 is a transverse section, taken in the plane of the line 4—4, Fig. 3. 60

Fig. 5 is a perspective view of one of the elements of the mechanism.

Fig. 6 is a perspective view of one of the friction elements; and

Fig. 7 is a detail vertical section illustrating the means employed to retain the cushioning parts in assembled relation for shipping, and to impart to the springs or spring units an initial compression for taking up wear of the friction elements. 65 70

In the drawings the center-sills or draft-sills of a car are indicated by the reference numeral 1. The illustrated form of these sills is, of course, to be regarded as typical and not as material to the invention. 75

Secured to the inner face of each of the sills 1, as by means of rivets, is a cheek-plate or draw-bar follower stop casting 2. These cheek-plates are preferably formed at the rear as well as at the front with inwardly extending stops 3 which, by overlappingly engaging adjacent movable parts that perform the functions of followers, serve to transmit to the underframe of the car the draft and buffing shocks after modification by the cushioning mechanism. Each of the cheek-plates 3 is also preferably provided with a longitudinally extending recess or way 4 for the reception of means for communicating draft forces from the coupler to the cushioning mechanism, such means, as shown, being most advantageously formed as a U-shaped yoke 5 which passes around the rear end of the cushioning mechanism and which has its arms, bars or branches disposed opposite each other horizontally so as to permit the elements of the cushioning mechanism to extend vertically a considerable distance. At their forward ends the arms of the yoke 5 are preferably slotted to receive a horizontally extending key 6 which also passes through a slot in the shank of the coupler 7, the yoke being thus made to move with the coupler when the latter is subjected to draft forces. 95 100

The cushioning mechanism embraced by the yoke involves springs, relatively movable friction members and means for pressing the relatively movable friction members together whenever the springs are compressed in response to the draft and buffing movements of the coupler. The inner fric-

tion member 8 is preferably in the form of a plate having its upper and under surfaces parallel and lying in horizontal planes, the forward portion of said member being somewhat reduced in width to thereby form a tongue 9 which may enter the clamping member 10 and to also form shoulders 11 which, by coming into engagement with the clamping member, are adapted to limit the compression of the springs 12 and thus prevent them from being broken or injured by being compressed until they are solid. At its rear end the inner friction member 8 engages, and, as shown, is preferably integrally fashioned with, a follower 13 upon which are seated the springs 12, said springs, which are preferably nested spring units, being arranged one above the other and being separated by the inner friction member 8. The follower 13, it will be understood, is drawn forward by the yoke 5 under the application of draft forces and in buffing is held stationary by the rear stops 3 of the cheek-plates.

The external friction members 14, which coöperate with the inner friction member, are preferably two in number, one being in slideable contact with the upper surface of the inner friction member and the other being similarly in contact with the under surface of the said inner friction member. In order to afford increased area of frictional surface, the external friction members are preferably provided with tongues or extensions 15 which enter the clamping member 10 and, overlappingly, engage the forward portion of the central friction member 8. The means for causing the external friction members 14 to press against the inner friction member preferably consist of a clamping or wedging member 10 having a central aperture 16 for the reception of the forward ends of the several friction members and having upper and lower inclines 17 which coöperate with and, preferably directly engage corresponding inclined faces 18 with which the external friction members 14 are respectively provided. At its forward end the clamping or wedging means 10 may be, and preferably is, provided with an integrally attached plate-like portion or follower 19 which in normal position of the parts and in buffing operations is engaged by the rear end of the coupler 7 and which when the coupler is subjected to draft engages the stationary stops 3 at the forward ends of the cheek-plates 2. The clamping means 10 and the external friction members 14 move together as a unit or in cluster, and these clustered parts are operatively interposed either between the springs 12 and the coupler 7, or between the springs and the follower stops 3 at the forward ends of the cheek-plates, depending upon whether the mechanism is resisting a buffing or a draft shock, the pressure of the external friction elements against the inner friction member varying directly with the compression of the springs which act upon the clustered parts 10 and 14. As shown, it is preferred that the pressure of the springs 12, instead of being communicated to the external friction elements 14 through the clamping member 10, shall be transmitted to said clamping member through the external friction members, the inner ends of the latter being seated on their respective springs which are assembled in the apparatus with sufficient initial compression to take up or compensate for wear of the parts. To attain desirable compactness the contact of the external friction members 14 with the inner friction member 8 preferably terminates at the forward ends of the springs 12. This arrangement permits springs of very large capacity to be employed without unduly increasing the vertical height of the cushioning mechanism.

In order to place the springs under the desired initial compression and also to afford a convenient means for retaining the parts in assembled relation for shipping, the forward end of the tongue 9 of the inner friction member may be provided with a threaded recess 20 which is in alignment with an opening 21 in the follower portion 19 of the clamping member 10. By passing a threaded bolt 22 through the opening 21 and screwing its threaded end into the threaded recess 20 of the inner friction member, as shown in Fig. 7, the springs 12 may be compressed, as will be readily understood. Before the coupler 7 and yoke 5 are connected to each other in completing the application of the draft gear to the railway vehicle, the bolt 22 is preferably removed, although it may be permitted to remain in place and slide in and out through the usual hole in the rear end of the coupler stem. To prevent such an upsetting of the metal around the threaded opening 20 as might render it difficult to subsequently engage the bolt 22 with the threads of the recess, an annular countersink 23 may encircle or border the outer end of the threaded recess.

In order to support the rear end of the draft gear it is preferred to employ a carrier plate 24 which is detachably connected to the sills of the car by means of bolts 25 and 26 which passes under and engages the lower spring 12. To prevent excessive upward movement of the mechanism a cover plate 26, which is secured to the center-sills and which lies closely above the upper spring 12, may be conveniently adopted. If in any instance it may seem desirable to afford special support for the forward end of the cushioning mechanism, a supporting bar, strap or plate 27 may be detachably connected to the sills 130

by bolts 28 for that purpose, the said strap being positioned so as to engage the under surface of the clamping member 10.

The application of the mechanism to a railway vehicle, or its removal therefrom should repairs become necessary, may be expeditiously accomplished with comparatively little labor. To apply the mechanism the springs, friction members and clamping member are brought into assembled relation and the springs are put under initial compression by means of the bolt 22. These parts thus connected are then inserted vertically between the bars or branches of the yoke 5 and positioned between the stops or lugs 3, the yoke having been theretofore inserted in the guideways 4 of the cheek-plates. The bolt 22 may then be removed and the supporting plates 24 and 27 may be secured to the sills of the car. Finally, the coupler 7 may be placed in position and connected to the yoke 5 by means of the transversely extending key 6.

In buffing, the clamping member 10 and the external friction members 14, which are preferably yieldingly supported against movement in one direction only, are forced rearwardly by the coupler 7, compressing the springs 12 against the follower 13, which is then seated on the rear follower stops 3, and thereby pressing the external friction members 14 against the inner friction member 8 to develop friction as the external friction members slide upon the inner friction member. Upon a cessation of the buffing force, the springs 12 expand and return the parts to normal position, the recoil of the springs being decreased by the braking effect of the friction between the coöperating friction elements.

In draft the clamping member 10 and external friction members 14 are held stationary by the forward stops 3 of the cheek plates, while the yoke 5 moves the follower 13 and inner friction member 8 forwardly. The springs 12 are thus compressed and the inner friction member is forced between the external friction members to develop friction in augmentation of the simple spring resistance and directly proportional thereto. In buffing as well as in draft the compression of the springs 12 is limited by the engagement of the outer end of the inner friction member 8 with the clamping member 10, as will be readily apparent.

I claim:

1. In a friction draft gear, the combination with an inner friction member, of friction members external thereto and contacting therewith and movable with respect thereto, and means for causing said external friction members to press inwardly against said inner friction member, said means in-

volving a plurality of springs arranged one above another, and said inner friction member extending between and serving to limit the compression of said springs. 65

2. In a friction draft gear, the combination with an inner friction member, of friction members external thereto and coöperating therewith, springs arranged one above another on opposite sides of said inner friction member, and means for operatively connecting said friction members and springs to a car coupler, said means involving horizontally aligned bars disposed at the sides of said friction members. 70 75

3. In a friction draft gear, the combination with a coupler, of relatively movable contacting friction members, a plurality of springs arranged one above another and operating when the coupler is moved in draft or buffing to apply pressure to said friction members, and means for operatively connecting said friction members and springs to the car coupler, said means involving horizontally aligned bars arranged at the sides of said friction members. 80 85

4. In a friction draft gear, the combination with an inner friction member, of friction members external thereto and contacting therewith and movable with respect thereto, a plurality of springs arranged one above another, and wedging means movable from normal position in one direction only 90 95 for causing said external friction elements to press inwardly.

5. In a friction draft gear, the combination with relatively movable contacting friction members, of a plurality of springs arranged one above another, and wedging means movable from normal position in one direction only for causing said friction members to be pressed together. 100

6. In a friction draft gear, the combination with an inner friction member, of friction members external thereto and contacting therewith, and a plurality of springs acting upon said external friction members, said inner friction member extending between said springs, and the contact of said external friction members with said inner friction member terminating at the proximate ends of the springs. 105 110

7. In a friction draft gear, the combination with a coupler, of relatively movable engaging friction members, a plurality of springs, and wedging means for causing the pressure of said springs to force said friction members together, said springs acting 115 simultaneously and independently to create pressure between said friction members and having their axes in the same vertical plane. 120

In testimony whereof I affix my signature.

GILBERT P. RITTER.
